ATTORNEY

UNITED STATES PATENT OFFICE

AUGUSTA M. BERGER, OF PALENVILLE, NEW YORK

SHOE LACE FASTENER

Application filed October 20, 1932. Serial No. 638,693.

This invention relates to a shoe lace fastener.

Although laced shoes are more comfortable than button shoes their appearance is often not as neat due to the loose lace ends and if the knot is not tied very tightly the loose ends become unfastened with the danger of stepping thereon in addition to the unsightly appearance. Various forms of fastening devices have been made but in general such devices are too bulky and cumbersome and must be affixed by either a shoemaker, repairman or by the manufacturer.

One of the objects of this invention is to provide a fastening device that may be affixed to the shoe by any individual.

A further object of the invention is to provide a shoe lace fastener that will be neat in appearance and one that will hold the loose ends of the bow knot from becoming un tied.

Referring to the drawing:

Figure 1 is a view in elevation of a device embodying the principles of my invention showing the same affixed to a shoe.

Figure 2 is an enlarged front view of my invention.

Figure 3 is an enlarged rear view of my invention.

Figure 4 is an enlarged sectional view of Figure 1 along line 4, 4, looking in the direction of the arrows.

In carrying out my invention I propose to provide a device which is small, simple and one which will satisfactorily hold the loose ends of the shoe laces A. The device consists of a metallic body portion 1 having a curved shank 2 and a head 3. Head 3 is adapted to loop over an elastic loop 4. The head 3 holds the ends of the elastic loop either by being compressed thereon or in any other well known manner. The elastic loop which may be made of either rubber, spring wire or other elastic material and is adapted to slip over the end of the curved

shank 2. The bottom of the curve of the shank of course is filled by the leather of the shoe B forming the backing against which the laces are held. This device is readily applied to a shoe by piercing near the top of the upper adjacent the top eyelet, two holes. The curved shank 2 is threaded through the holes so that the end protrudes. The end of the curved shank 2 is threaded and is adapted to receive a knob 5. This knob 5 has a twofold purpose. It prevents the slipping off of the elastic loop 4 and also prevents the ripping of the stockings in the case of crossing of the feet. The knob 5 may be made integral if desired with curved shank 2. The elastic and metallic body portion are preferably made in various colors so that there will be devices for brown shoes, black shoes, etc., in order that they will be inconspicuous.

What I claim is:

1. A shoe lace fastener comprising a body portion and a shank, a yielding member secured to said body portion, said shank adapted to be passed through a portion of the shoe upper whereby the end of the shank protrudes to permit said yielding member to be looped over the loose ends of the shoe lace and around the protruding end of the shank.

2. A shoe lace fastener comprising a body portion and a curved shank integral therewith, a looped yielding member secured to said body portion, the body portion and looped member adapted to be secured exteriorly of the shoe upper and the shank adapted to be passed through the shoe upper with its end protruding to permit said yielding member to be looped over the loose ends of the shoe lace and around the protruding end of the shank.

3. A shoe lace fastener comprising a body portion and a shank, a yielding member secured to said body portion, said shank adapted to be passed through a portion of

the shoe upper whereby the end of the shank
protrudes to permit said yielding member
to be looped over the loose ends of the shoe
lace and around the protruding end of the
5 shank, and a knob on the protruding end of
the shank.

Signed at New York in the county of
New York and State of New York this 13th
day of October A. D. 1932.
